US0D1097142S

(12) **United States Design Patent** (10) **Patent No.:** **US D1,097,142 S**
(45) **Date of Patent:** ** *Oct. 7, 2025

(54) **COLOSTRUM COLLECTOR**

(71) Applicant: **SHIYUAN TRADING CO., LIMITED**, Kwun Tong Kln (HK)

(72) Inventor: **Yi Zhong Dai**, Kwun Tong Kln (HK)

(73) Assignee: **SHIYUAN TRADING CO., LIMITED**, Kwun Tong Kln (HK)

(*) Notice: This patent is subject to a terminal disclaimer.

(**) Term: **15 Years**

(21) Appl. No.: **29/930,926**

(22) Filed: **Mar. 4, 2024**

(30) **Foreign Application Priority Data**

Jan. 29, 2024 (EM) 015048894-0001

(51) **LOC (15) Cl.** **24-02**

(52) **U.S. Cl.**

USPC **D24/121**
